Primary Examiner — Holly Bayham*Assistant Examiner* — Rhea Shields(57) **CLAIM**

The ornamental design for an electrosurgical generator, as shown and described.

DESCRIPTION

FIG. 1 is a perspective view of an electrosurgical generator in accordance with a first embodiment of the present design; FIG. 2 is a front view of the electrosurgical generator of FIG. 1;

FIG. 3 is a rear view of the electrosurgical generator of FIG. 1;

FIG. 4 is a left side view of the electrosurgical generator of FIG. 1;

FIG. 5 is a right side view of the electrosurgical generator of FIG. 1;

FIG. 6 is a top view of the electrosurgical generator of FIG. 1;

FIG. 7 is a bottom view of the electrosurgical generator of FIG. 1;

FIG. 8 is a perspective view of an electrosurgical generator in accordance with a second embodiment of the present design; FIG. 9 is a front view of the electrosurgical generator of FIG. 8;

FIG. 10 is a perspective view of an electrosurgical generator in accordance with a third embodiment of the present design; and,

FIG. 11 is a front view of the electrosurgical generator of FIG. 10.

In the drawings, the broken lines are for the purpose of illustrating environment only and form no part of the claimed design.
